CURB BIT FOR BRIDLE

Harold M. Poole, Medina, Wash.
(Rte. 2, Torrington, Wyo.)

Filed Nov. 20, 1958, Ser. No. 775,150

2 Claims. (Cl. 54—7)

My invention relates to curb bits for bridles and the primary object of my invention is to provide a curb bit by which lever action can be exerted through tensioning of the bridle reins to control a horse without exerting downward pressure by way of the head strap of the bridle of the top of the horse's head just back of the ears.

Other objects are to provide a curb bit which is simple and strong in construction, serviceable and efficient in operation, humane and easy on the animal on which it is used, easy to clean and keep in proper condition for use, and one which is similar in appearance to a conventional curb bit.

Other objects of my invention will be apparent from the following description taken in connection with the accompanying drawings.

The conventional curb bit comprises a one piece bar or mouth piece having two cheek pieces rigid with and extending crosswise of its respective ends. Each cheek piece comprises a shorter upper cheek piece member and a longer lower cheek piece member. The lower end portions of the head strap of a bridle are connected with the upper ends of the upper cheek piece members. Reins are connected with the lower ends of the lower cheek piece members. The upper and lower cheek piece members at each side are rigid relative to each other. They function like levers on the ends of the bit bar. This conventional curb bit is a bit with lever action capable of increasing the force exerted by pulling on the reins and localizing this force, to a large extent, on the sensitive bars of the animal's posterior jaw. In the use of this conventional curb bit, when a pull is exerted on the reins both the lower and upper cheek piece members are rotatively moved and pressure is applied by the head strap of the bridle to the top or poll of the animal's head just back of the ears. This pressure, thus exerted on the ear muscles and nerves, confuses the horse and is objectionable in that it causes the horse to lay back its ears and thrust its head forward. This gives the horse an undesirable appearance and has an adverse effect on its balance.

It is generally recognized that this downward pressure exerted by the head strap of the bridle on the top of a horse's head in the use of a conventional or ordinary curb bit is undesirable. On page 54 of "Elements of Hippology," written by F. C. Marshall, Captain, Fifteenth Calvary, and prepared under the direction of the Department of Tactics, United States Military Academy, West Point, N.Y., 1906, the author states, "The ordinary curb bit exerts a downward pressure on the poll, which increases as the curb chain is loosened, allowing the upper branch to revolve further forward and downward. This is objectionable, but as no bit has ever been devised that removes it without introducing more objectionable features, it is a condition that must be accepted for the present."

In accordance with my invention I provide a curb bit in which the upper cheek pieces are pivotally connected with the respective ends of the bit bar so that

2

there will not be any downward pull pressure exerted by the head strap of the bridle when a pull is exerted on the reins and the horse will react to the pull on the reins by keeping its ears in a forward position and arching its neck and will not fight the bit.

In the accompanying drawings:

Figure 1 is a side elevational view illustrating by dotted lines the head of a horse having thereon a bridle equipped with a curb bit constructed in accordance with my invention.

Fig. 2 is an edge view of my curb bit looking in the direction of broken line 2—2 of Fig. 3.

Fig. 3 is an elevation of my bit looking in the direction of broken line 3—3 of Fig. 2.

Fig. 4 is an exploded fragmentary perspective view showing parts of my curb bit.

Fig. 5 is a sectional view, with parts in elevation, taken substantially on broken line 5—5 of Fig. 2.

Like reference numerals refer to like parts throughout the several views.

My bit comprises a bit bar 10 having an arch shaped port 11 midway between its two ends. When the bit is at rest in the animal's mouth the port 11 lies on the tongue. When a pull is exerted on the bit to stop or control the animal the port 11 revolves upward and forward and away from the tongue providing greater tongue freedom. The bit bar 10 has an enlargement or flange 12 at each end thereof and each flanged end portion terminates in a flat end surface 13, Fig. 4, provided with an axial threaded hole 14.

Two lower cheek pieces 15 and 16 are integral with or rigidly attached to the respective ends of the bit bar 10 and extend approximately perpendicularly outward from said bit bar in the same direction. The upper end of each lower cheek piece 15 and 16 is shaped to provide an approximately semi-circular shield and stop member 17. Two stop surfaces 18 and 19 are provided by the shield 17.

Two upper cheek pieces 20 and 21 of shorter length than the lower cheek pieces are pivotally connected with the respective ends of the bit bar 10 and extend approximately perpendicularly away from said bit bar in the opposite direction from the respective lower cheek pieces 15 and 16. The lower end portion of each upper cheek piece 20 and 21 is of partially cylindrical external shape to fit within the adjacent shield member 17 and is drilled, as best shown in Fig. 4 to provide a counterbore 22 of fairly large diameter, a tubular bearing member 23 of smaller diameter than the counterbore 22 and a flat shoulder 24.

A shouldered bearing screw comprising a threaded portion 25, a shoulder 26, a cylindrical bearing member 27, and a head 28 is adapted to extend through the counterbored portion of each upper cheek piece and is threaded into the perforation 14 in the adjacent end of the bit bar 10. The shoulder 26 of this bearing screw abuts against the flat end surface 13 of the bit bar and the parts 27 and 28 fit within the respective bearing member 23 and counterbore 22 of the upper cheek piece forming an adequate pivotal bearing for the upper cheek piece.

The particular structure of the adjoining end portions of my bit bar and cheek pieces makes it possible, in a curb bit having pivotally mounted upper cheek pieces, to keep the upper and lower cheek piece members in the same plane and to avoid having thick and bulky parts at the ends of the bit bar. The stop members 18 and 19 limit pivotal movement, in both directions, of the upper cheek pieces and make bridles which are equipped with my curb bit easier to handle when they are not on an animal or are being applied to an animal than they would be in the absence of these stop members. The pivotal mounting of the upper cheek pieces 20 and

21 does not substantially change the conventional appearance of the curb bit.

Each upper cheek piece 20 and 21 terminates at its upper end in a ring 30 to which the head strap 31 of a bridle is attached. The head strap 31 passes over the horse's head just back of the ears when the bridle is in use.

A rearwardly extending arm 32 is provided on each lower cheek piece 15 and 16 near the end thereof which is rigid with the bit bar 10 and a perforation 33 is provided in each arm 32 to receive a curb chain 34. The curb chain 34 passes around the lower portion of the animal's jaw at the location of the chin groove. The lower end of each lower cheek piece 15 and 16 carries a ring 35 to which a bridle rein 36 is secured. The curb chain 34 is adjustable in the usual manner and cooperates as a fulcrum member in applying the bit bar to the bars of the animal's mouth when a pull is exerted on the reins 36.

With a conventional curb bit, which has all of its cheek pieces rigid with the bit bar, when a pull is exerted on the reins the fulcrum is at the upper ends of the upper cheek pieces and these upper cheek pieces tend to rotatively move forwardly with the result that a downward pull is exerted on the head strap of the bridle. This pull essentially produces a downward pressure of the head strap on the top of the horse's head near the base of the ears. This pressure causes the horse to lay back its ears and protrude its head forwardly or stick out its nose.

My bit has the upper cheek pieces pivotally connected with the respective ends of the bit bar so that when tension is applied through the reins to the lower ends of the lower cheek pieces the bit bar will be rotatively moved, the curb chain will be tensioned, and the bit bar 10 will be drawn against the sensitive bars of the animal's mouth without exerting a downward pull on the head strap. Under these conditions the horse will keep its ears pointed forwardly and will arch its neck thereby presenting a better appearance and maintaining a better condition of balance. Also when the controlling force is thus applied only in one place, namely on the bars of the mouth, less force is needed to control the horse, the horse is not confused by the application of a head pressure which does not have anything to do with controlling or stopping him and for these reasons the bit is more humane.

The foregoing description and accompanying drawings clearly disclose a preferred embodiment of my invention but it will be understood that changes may be made within the scope of the following claims.

I claim:

1. A curb bit comprising a bit bar having two flat end

portions each perpendicular to the axis of the bit bar and each provided with an axial threaded perforation; two upper cheek pieces having perforated end portions positioned against the respective flat end portions of the bit bar; a shoulder screw threaded into each of said axial perforations and extending through each of said perforated end portions pivotally to secure the perforated end portions of the upper cheek pieces to the bit bar with said upper cheek pieces extending outwardly in one direction from the bit bar; two stop members provided on each end of said bit bar limiting pivotal movement in two directions of the respective upper cheek pieces; and two lower cheek pieces integral with the respective end portions of the bit bar and extending outwardly in a substantially opposite direction from the bit bar.

2. A curb bit comprising a bit bar; a flange member providing an enlargement at each end of said bit bar, each flanged end of said bit bar terminating in a flat end surface perpendicular to the axis of the bit bar and each end of said bit bar having an axial threaded perforation therein; two lower cheek pieces integral with the respective flanged end portions of said bit bar and extending outwardly in one direction from said bit bar, each lower cheek piece terminating at its upper end in an integral concave shield and stop member which is offset outwardly from the plane of the adjacent flat end surface and extends around the margin of approximately the lower half of the adjacent end flange; two upwardly extending upper cheek pieces each having a rounded lower

end portion positioned within one shield and stop member with the inner face of the upper cheek piece resting against the adjacent flat end surface of the bit bar, the lower end of each upper cheek piece having a transverse counterbored hole therein forming a larger outer counterbore and a shoulder and a smaller inner bearing sleeve; and a shoulder screw extending through the counterbored hole in each upper cheek piece and threaded into the axial perforation in the adjacent end portion of the bit bar, each shoulder screw having a head seated in the counterbore of the upper cheek piece and a bearing shank fitting snugly within the bearing sleeve of said upper cheek piece and a shoulder abutting against the adjacent flat end of the bit bar.
